MEDICAMENT DISPENSING CONTAINER WITH TWIST-OFF CLOSURE

Stanley F. Payton, Pottstown, Pa., assignor to American Home Products Corp., New York, N.Y.

Filed Jan. 30, 1973, Ser. No. 327,891

Term of patent 14 years

Int. Cl. D24—04

U.S. Cl. D83—1 Q

FIG. 4

FIG. 5

FIG. 6

FIG. 1 is a side elevational view of a medicament dispensing container with twist-off closure embodying my new design, the opposite side being the same in appearance as the side shown;

FIG. 2 is a top plan view;

FIG. 3 is a fragmentary, elevational view looking from the right of FIG. 1;

FIG. 4 is a bottom plan view;

FIG. 5 is a sectional view taken along 5—5 of FIG. 1; and

FIG. 6 is a sectional view taken along the line 6—6 of FIG. 1.

I claim:

The ornamental design for a medicament dispensing container with twist-off closure, as shown and described.
